UNITED STATES PATENT OFFICE.

FREDERICK E. GLAZE, OF VICTOR, COLORADO, ASSIGNOR TO THE EUREKA DRILL STEEL COMPANY, OF CRIPPLE CREEK, COLORADO, A CORPORATION OF COLORADO.

ROCK-DRILL.

No. 849,229.

Specification of Letters Patent.

Patented April 2, 1907.

Application filed January 31, 1906. Serial No. 298,878.

To all whom it may concern:

Be it known that I, FREDERICK E. GLAZE, a citizen of the United States, and a resident of Victor, in the county of Teller and State of Colorado, have invented a new and Improved Rock-Drill, of which the following is a specification.

My invention relates to drills in general, but more particularly drills intended for boring or drilling rock.

The object had in view is to provide or construct boring and drilling tools with means rendering them self-cleaning—that is, adapting them for removal of the dust and chippings during operation thereof.

The invention consists of the novel and improved construction, which will hereinafter be fully described, and illustrated by the accompanying drawings.

In the drawings, Figures 1 and 2 show drills constructed with parallel straight ribs extending from their cutting ends to substantially the shank or heel ends with my cleaning means shown applied thereto, but one means in modified form. Figs. 3 and 4 illustrate twist-drills with modified forms of the cleaning means; and Figs. 5, 6, 7, and 8 are transverse sectional views taken, respectively, through the ribbed portions of the drills illustrated in Figs. 1, 2, 3, and 4.

It is well known that in drilling flat or back holes in rock with machine-drills not employing some method of forcing water or air into the holes whereby to clean them of dust and chippings great difficulty is experienced through the dust, &c., packing around the drill, causing it to bind in the hole thereby rendering it very difficult and at times almost impossible to withdraw the drill from the hole.

Now the object of my invention is to construct drills in general, of whatsoever form thereof, having helical or other form of groove or rib, with obstructions in the grooves or on the ribs operating to eject the dust or chip-cuttings from the hole during drilling action and effective for removal of all such cuttings upon removal of the drill from the hole.

In the practice of my invention I may provide or construct drills with the aforesaid obstruction arranged projecting into the drill-grooves from the sides of the ribs and

with the same located opposite or in staggering arrangement with respect to those in the adjacent grooves, or they may be in the nature of struck up or otherwise formed walls, disposed transversely in the grooves, extending from rib to rib or part way across the groove, as may be desired and best adapted for the use intended in drilling holes in rock or other material.

In my drawings I have illustrated my invention applied to straight-ribbed and twist-drills; but I do not desire to be restricted thereto in the use of my invention, since its conception comprehends similar dust and chip removing means on any form of drill to which the said means are applicable. I wish it further understood that the obstruction shown on one form of drill in my drawings may be changed to another form of obstruction illustrated or of substantially similar construction without departing from the spirit of my invention.

In describing my invention as illustrated in the drawings I would first refer to Fig. 1 thereof, showing a common form of drill A, having straight longitudinal grooves or channels B and similar ribs C. In the grooves or channels B, I provide raised bur obstructions D—such, for instance, as may be cut with a round or "bull-nosed" chisel. The bur obstructions are preferably made extending from rib to rib and with the cut or barb side facing backwardly from the bit to the shank of the drill. The bur obstructions D in any groove or channel B are preferably spaced apart less than a full working stroke of the drilling-machine. In adjacent grooves or channels they are preferably located in staggered arrangement, substantially as shown in Fig. 1. Obviously the obstructions D in the channels B may be otherwise formed—as, for instance, by rolls or otherwise—when the drill is manufactured.

In Fig. 2 I illustrate forms of obstructions, one, E, consisting of burs cut from opposite sides of the ribs C, another, F, in the nature of a projection extending out into the drill-groove or channel C, and still another, G, consisting of a bur or lug, leaving a space H between its under side and the bottom of the groove or channel.

Fig. 3 illustrates another form of obstruction applied to a twist-drill, the same con-

sisting of staggered arrangement of fillings I in the grooves or channels B, made integral with the twisted ribs C.

In Fig. 4 I show a twist-drill having burs J 5 and lugs K constructed similar to the like burs E and lugs F. (Illustrated in Fig. 2.) It will be noticed that in this figure of the drawings the burs or lugs are located on one side of the ribs, though obviously I do not desire to be so restricted in the use of my invention.

It is intended that all the burs and lugs hereinbefore described shall be formed providing abrupt or substantially perpendicular faces next toward the drill-shank and 15 with faces looking toward the bit or cutting

end of the drill, preferably sloping to the bottom or side of the grooves or channels.

The construction and use of my invention will be understood from the above description.

What I claim is—

A drill constructed with grooves and ribs, and a series of transversely-disposed obstructions in the grooves, the obstructions being formed integrally connecting two adjacent 25 ribs, substantially as shown and described.

FREDERICK E. GLAZE.
